DESIGN FOR A WORK-ILLUMINATING TOOL

Robert S. Rains, Los Angeles, Calif., assignor to
R-W Manufacturing Company, Los Angeles,
Calif., a firm

Application June 15, 1945, Serial No. 120,118

Term of patent 3½ years

(Cl. D48—24)

To all whom it may concern:

Be it known that I, Robert S. Rains, a citizen of the United States and resident of the city of Los Angeles, county of Los Angeles, State of California, have invented a new, original, and ornamental Design for a Work-Illuminating Tool, of which the following is a specification, reference being had to the accompanying drawing, forming a part thereof, in which:

Fig. 1 is a plan view of a work-illuminating tool, showing my new design;

Fig. 2 is a side elevation;

Fig. 3 is the left-hand view; and

Fig. 4 is the right-hand view thereof.

I claim:

The ornamental design for a work-illuminating tool, substantially as shown.

ROBERT S. RAINS.
